GRAPHICAL RECORDER

Richard M. Kemplin, Altadena, Calif., assignor to F. L. Moseley Co., a corporation of California

Filed Nov. 12, 1963, Ser. No. 77,338

Term of patent 14 years

(Cl. D26—14)

Fig. 1.

Fig. 2

Fig. 3.

FIG. 1 is a perspective view of a graphical recorder, showing my new design and illustrating the right side, front and top thereof;

FIG. 2 is a view of the left side thereof; and

FIG. 3 is a rear elevation thereof.

The dominant features of my design reside in the portions shown in full lines. The broken line showing of the chart in FIG. 1 is for illustrative purposes only.

I claim:

The ornamental design for a graphical recorder, as shown and described.
